(57) **CLAIM**

The ornamental design for a combined flower-designed ultrasound thimblette and fingertip medical device, as shown and described.

DESCRIPTION

FIG. 1 is a top perspective view of the (combined ultrasound thimblette and fingertip medical device), in accordance with an embodiment of the invention;
FIG. 2 is a top plan view of the (combined flower-designed ultrasound thimblette and fingertip medical device), in accordance with an embodiment of the invention;

FIG. 3 is a left elevation view of the (combined flower-designed ultrasound thimblette and fingertip medical device), in accordance with an embodiment of the invention;
FIG. 4 is a left elevation view of the (combined flower-designed ultrasound thimblette and fingertip medical device), in accordance with an embodiment of the invention;
FIG. 5 is a front elevation view of the (combined flower-designed ultrasound thimblette and fingertip medical device), in accordance with an embodiment of the invention;
FIG. 6 is a rear elevation view of the (combined flower-designed ultrasound thimblette and fingertip medical device), in accordance with an embodiment of the invention;
FIG. 7 is an exploded perspective view of the (combined flower-designed ultrasound thimblette and fingertip medical device), in accordance with an embodiment of the invention;
FIG. 8 is a perspective view of the fingertip of an environmental feature of the (combined flower-designed ultrasound thimblette and fingertip medical device), in accordance with an embodiment of the invention;
FIG. 9 is a top perspective view of the (combined ultrasound thimblette and fingertip medical device), in accordance with another embodiment of the invention;
FIG. 10 is a top plan view of the (combined flower-designed ultrasound thimblette and fingertip medical device), in accordance with another embodiment of the invention;
FIG. 11 is a left elevation view of the (combined flower-designed ultrasound thimblette and fingertip medical device), in accordance with another embodiment of the invention;
FIG. 12 is a left elevation view of the (combined flower-designed ultrasound thimblette and fingertip medical device), in accordance with another embodiment of the invention;
FIG. 13 is a front elevation view of the (combined flower-designed ultrasound thimblette and fingertip medical device), in accordance with another embodiment of the invention;
FIG. 14 is a rear elevation view of the (combined flower-designed ultrasound thimblette and fingertip medical device), in accordance with another embodiment of the invention;
FIG. 15 is an exploded perspective view of the (combined flower-designed ultrasound thimblette and fingertip medical device), in accordance with another embodiment of the invention; and,
FIG. 16 is a perspective view of the fingertip of an environmental feature of the (combined flower-designed ultrasound thimblette and fingertip medical device), in accordance with another embodiment of the invention.

The broken lines are included for the purpose of illustrating environment and portions of the combined flower-designed ultrasound thimblette and fingertip medical device that form no part of the claimed design.
